FIG. 1 is a perspective view of a wheelbarrow showing our new design;
 FIG. 2 is a top view thereof;

FIG. 3 is a bottom view thereof;

FIG. 4 is a front view thereof;

FIG. 5 is a back view thereof;

FIG. 6 is a left side view thereof; and,

FIG. 7 is a right side view thereof.

The broken lines shown in the drawings are included for the purpose of illustrating unclaimed portions of the wheelbarrow and form no part of the claimed design.

1 Claim, 7 Drawing Sheets
